UNITED STATES PATENT OFFICE.

WILLIAM W. ALLEN, OF SLOATSBURG, NEW YORK, ASSIGNOR TO
STANDARD EQUIPMENT COMPANY, OF JERSEY CITY, NEW JERSEY,
A CORPORATION OF NEW JERSEY.

RAILWAY-SWITCH.

No. 827,405.

Specification of Letters Patent.

Patented July 31, 1906.

Application filed December 18, 1905. Serial No. 292,131.

To all whom it may concern:

Be it known that I, WILLIAM W. ALLEN, a citizen of the United States, residing at Sloatsburg, in the county of Rockland, in the State of New York, have invented certain new and useful Improvements in Railway-Switches, of which the following is a specification, reference being had to the accompanying drawings, forming a part hereof.

This invention relates to the slide-plates upon which the switch-tongue moves and upon which the rail is mounted. Such slide-plates are commonly provided with risers, which lift the switch-point substantially to the level of the rail-flange, so that it may move partly over the flange and lie snugly against the rail-head. Such risers are sometimes formed by striking up the plates from the under side, but this reduces the width of the bearing of the plates upon the ties and is therefore objectionable, and, moreover, the shoulder formed at the end of such riser is not a square shoulder, and therefore does not furnish a proper stop for the rail-flange. In some cases also such risers have been formed separately and secured to the plates by rivets and otherwise; but the securing means frequently give way in use, and trouble is thereby occasioned.

It is the object of this invention to provide a slide-plate which shall be free from all of the objections above enumerated and shall, moreover, furnish adequate stops for the rail-flanges on opposite sides thereof.

In accordance with the invention the improved slide-plate is formed, preferably, by rolling with a continuous flat under surface and an integral riser on its upper surface. The riser is then cut out to form a seat for the rail-flange, and it may also be cut out to form a seat for the rail-brace, the shoulders thus formed being square, and therefore constituting adequate stops for the rail and for the rail-brace, so that lateral movement of the rail upon the plate is practically impossible.

The invention will be more fully explained hereinafter with reference to the accompanying drawings in which it is illustrated, and in which—

Figure 1 is a view showing the slide-plate and rail-brace in elevation and the rail and switch-tongue in section. Fig. 2 is a plan view of the slide-plate. Fig. 3 is a view in

section on the plane indicated by the line 3 3. 55 of Fig. 2.

As shown in the drawings, the slide-plate *a* is a substantial plate of metal having a continuous flat under surface *b*, as clearly shown in Fig. 3, and having on its upper surface an integral riser *c*. This plate, with its riser, is most conveniently formed by rolling a plate of suitable dimensions, and in this case the riser extends from end to end of the plate-body *a*. It is necessary that the upper surface of the riser shall be approximately on the same level as the upper surface of the rail-flange at its edge. Consequently the riser after being formed, as stated, is cut out down to the upper surface of the plate-body *a* to form a seat for the rail, square shoulders being thereby formed at *d* and *e* as stops to cooperate with the rail-flange and hold the rail from lateral movement. As these stops are integral with the body of the plate and are also square, they hold the rail firmly against lateral movement in either direction. The riser may also be cut out, as on the lines *f* and *g*, to form a seat for the rail-brace, the square shoulder *g* forming an adequate stop for the rail-brace, even if it is not properly held by spiking.

It will be understood that the rail *h* is seated upon the surface of the body portion *a* of the plate, as at *d* *e*, and that the switch-tongue *i* slides upon the upper surface of the riser, being suitably planed off, as usual, to move partly over the rail-flange and snugly against the rail-head. The rail-brace *k* supports the rail, as usual, and is seated, as at *f* *g*, upon the plate-body.

I claim as my invention—

1. A slide-plate for railway-switches having a continuous, flat under surface and upon its upper surface an integral riser, such riser being cut away to the upper surface of the plate-body to form a seat for the rail, with square shoulders at each side thereof and being also cut away to the upper surface of the plate-body to form a seat for the rail-brace. 100

2. A slide-plate for railway-switches having upon its upper surface an integral riser, such riser being cut away to the upper surface of the plate-body to form a seat for the rail with square shoulders at each side thereof and bearing directly against the rail. 105

3. A slide-plate for railway-switches having upon its upper surface an integral riser,

such riser being cut away to the upper surface of the plate-body to form a seat for the rail with a square shoulder at each side thereof and being also cut away to the upper surface of the plate-body to form a seat for the rail-brace with a square shoulder.

4. The combination with a rail and a movable switch-tongue of a slide-plate having a continuous, flat under surface and upon its upper surface an integral riser to support the switch-tongue, such riser being cut away to the upper surface of the plate-body to form a seat for the rail with a square shoulder at each side thereof and bearing directly against the rail.

5. The combination with a rail, a movable switch-tongue and a rail-brace, of a slide-plate having an integral riser to support the switch-tongue, such riser being cut away to the upper surface of the plate-body 20 to form a seat for the rail with a square shoulder at each side thereof and being also cut away to the upper surface of the plate-body to form a seat for the rail-brace.

This specification signed and witnessed 25 this 14th day of December, 1905.

WILLIAM W. ALLEN.
